CONVERTIBLE COUCH, SETTEE, DIVAN,
AND THE LIKE

Jack Unterhalter, Johannesburg, Union of South Africa; assignor to Rosydoze Bedding Company (Proprietary) Limited, Johannesburg, Transvaal, Union of South Africa

Application-September 8, 1947, Serial No. 772,842
In the Union of South Africa October 10, 1946

2 Claims. (Cl. 5—20)

1

This invention relates to studio couches, settees, divans and the like of the type which is convertible into two bedsteads.

In these articles of furniture, it is usual for the normal seating area of the couch or the like to constitute one of the two bedsteads and for the other bedstead to comprise a separate frame movable from a position in which it is stowed away below the couch or the like into an exposed position alongside of, or separated from, the latter. In this position the movable bedstead is ready to receive a mattress which may previously have constituted the upholstered removable seating of the couch or the like or which may have been stowed separately within the framework of the movable bedstead.

Hitherto, inconvenience has been experienced in positioning the mattress on the movable bedstead, an operation which normally involves lifting of the mattress from its position within the framework of the movable bedstead or upon the couch and placing it on the movable bedstead.

The object of the present invention is to provide means whereby this difficulty may be overcome.

According to the invention, I provide a studio couch, settee, divan or the like of the type stated in which the movable bedstead comprises a lower main framework and an upper mattress-supporting frame to which a mattress may be strapped or otherwise fastened, said upper frame being pivotally supported at either end of the main framework so that it may be rotated through 180° from a position in which the mattress is suspended downwards from its frame and housed in the interior of the main framework, into a position in which said mattress lies above and on top of its frame in an exposed position ready for use.

Preferably, means is provided whereby said upper frame may be raised vertically from said main framework prior to rotation of the former and lowered back thereon after rotation has taken place.

The raising and lowering means aforesaid may comprise a lazy-tongs mechanism operable by hand or foot pressure, and the upper frame may be pivotally mounted on horizontal end rails which are adapted to be raised from and lowered onto the main framework by means of said lazy-tongs mechanism on which they are carried.

Spring means may be provided for assisting the raising of the upper frame. Said means may conveniently comprise a coil spring or springs.

disposed horizontally between the upper ends of crossed levers forming the lazy-tongs mechanism.

The invention will be further described with reference to the accompanying drawings in which:

Fig. 1 is a perspective view of the movable bedstead of a convertible divan, with the mattress in position for normal use;

10 Fig. 2 is an end elevation of the movable bedstead shown in Fig. 1 with the mattress in the position it normally occupies when the bedstead is stowed within the framework of the divan, a part of which is also shown;

15 Fig. 3 is a view similar to that shown in Fig. 2 but with the mattress and upper frame of the bedstead in the process of being rotated about its pivots;

20 Fig. 4 is an end elevation of the movable bedstead shown in the previous figures ready for normal use and positioned alongside the divan;

Fig. 5 is an end elevation of the movable bedstead of a convertible divan showing another embodiment of the invention;

25 Referring to Figs. 1 to 4:

The movable bedstead comprises an upper frame 1 carrying the mattress 2, which is supported on a lower frame 3 provided with castors 4. Each end of the movable bedstead is provided with a lazy-tongs arrangement comprising a pair of levers 5, 6 the upper ends of which are pivotally connected at 7, 8 to a rail 9 on which the upper frame 1 is pivotally mounted at 10. The lower ends of the levers 5, 6 are pivotally connected at 11, 12 to the lower end rail 13 of the frame 3. The levers 5, 6 are also pivotally connected to each other at 14 and the pivots 7, 11 are slidably mounted within grooves 15, 16 provided in the rails 9, 13 respectively.

40 A bell crank lever 17 is provided at one end of the bedstead and is mounted on a shaft 18 (Fig. 1) running the full length of the bedstead and supported on the end rails 13. The bell crank lever 17 is operatively connected to the pivot 14 of the levers 5, 6 at the one end of the bedstead, through a link 19 and is adapted to operate the levers 5, 6 at the other end through the shaft 18, lever 20 and link 21 (Fig. 1).

45 The upper frame 1 is provided with supporting lugs 22 along its sides adapted to support the frame 1 on the side rails 23 of the lower frame 3. A tension spring 24 is provided between the upper ends of the levers 5, 6 and is adapted to constrain the said ends of the levers 5, 6 toward each other.

The movable bedstead is connected to the divan 25 in normal manner i. e. by means of a lazy-tongs mechanism 26.

When not in use the movable bedstead is normally stowed within the framework of the divan 25. In this position the upper frame 1 of the movable bedstead is supported upside down on the side rails 23 of the lower frame 3 by the supporting lugs 22 which rest on their faces 22a (Fig. 3) and the mattress which is strapped to the frame 1 is suspended below it within the frame 3 as shown in Fig. 2.

When required for use, the movable bedstead is withdrawn from the framework of the divan 25 to the position shown in Fig. 2. Foot pressure is then applied to the bell crank lever 17 which raises the rails 9 through the levers 5, 6 and with it also the upper frame 1 which is pivotally connected to the rails at 10, until it reaches the position shown in Fig. 3. In this position the upper frame 1 is no longer supported on the lower frame 3 and is capable of being swung around the pivots 10 until the mattress occupies its normal position with respect to the sprung frame 1. At this stage pressure on the bell crank lever 17 is released and the frame 1 together with the mattress 2 is lowered until the faces 22b of the supporting lugs 22 come to rest on the side rails 23 in the position shown in Fig. 4.

The movable bedstead is now ready for use and may be positioned directly alongside the divan to form a double bed or separated from it to form a single bed by removing the pins 26a (Fig. 3).

When the movable bedstead is no longer required, the operation described above is reversed and the upper frame 1 and mattress 2 will resume the position shown in Fig. 2 ready for stowing under the divan 25.

It will be appreciated that the action of the tension springs 24 aids in the lifting of the upper sprung frame and mattress by the lever arrangement aforesaid and only a relatively slight pressure on the bell crank lever is required.

Referring now to Fig. 5 in which parts similar to those shown in Figs. 1 to 4 are designated by like numerals:

The upper frame 1 is eccentrically mounted at each end on a flanged wheel 27 adapted to move transversely across top end rails 28 of the lower frame 3 of the bedstead. Levers 29 (one at each end) are pivotally connected to the lower frame 3 at 30 and to the upper frame 1 at 31. Straps 32 are fixed to the one side 33 of the upper frame 1 and supporting lugs 34 are provided on the same side.

The upper frame 1 is normally supported in a horizontal position by means of the wheels 27 and the supporting lugs 34 which latter rest on the one side of the lower frame 3.

In order to bring the mattress into position either on top of the frame 1 or below it within the lower frame 3, the side 33 of the upper frame 1 is raised from that side of the lower frame 3 on which the supporting lugs 34 rest, by means of the straps 32, until the frame 1 reaches a vertical position. Thereafter the side 33 of the frame 1 is lowered onto the opposite side of the frame 3 until the lugs 34 come to rest on it.

During this process the wheels 27 will move along the rails 28 toward the opposite side of the frame 3 and the frame 1 will rotate about the pivot 31 through 180°.

By virtue of this invention, it has been made

possible to lower the upper sprung frame of the movable bedstead and the mattress, within the lower frame to such an extent that an appreciable clearance is provided between the said upper frame and the framework of the divan within which the movable bedstead is stowed. This space can conveniently be used for stowing the bedding which has hitherto required a special place of safekeeping when not in use.

I claim:

1. An article of furniture of the type stated having one bedstead constituted by the normal seating area of the article of furniture and another bedstead comprising a separate frame, movable from a position in which it is stowed away within the article of furniture into an exposed position alongside of the latter; in which the movable bedstead comprises a lower main framework; an upper mattress supporting frame to which a mattress is attachable, a pair of horizontal end rails on and between which the mattress-supporting frame is pivotally mounted; lever means for raising the horizontal end rails, and with them the mattress supporting frame, vertically from said main framework from a position in which the mattress is suspended downwards from its frame and housed in the interior of the main framework, into a position in which the mattress-supporting frame may be rotated about its pivots through 180° so that the mattress lies above and on top of its frame; and lever means for thereafter lowering said horizontal end rails down upon said main framework.

2. An article of furniture of the type stated having one bedstead constituted by the normal seating area of the article of furniture and another bedstead comprising a separate frame movable from a position in which it is stowed away within the article of furniture into an exposed position alongside of the latter; in which the movable bedstead comprises a lower main frame mounted on castors and provided in the bottom portion of each end with a horizontal slot; a pair of horizontal rails each of which is provided at one end with a horizontal slot; an upper mattress-supporting frame pivotally mounted on and between the horizontal end rails; supporting lugs on the upper frame for supporting it on the sides of the lower main frame in a position where

the two horizontal slots at each end of article of furniture (i. e. one in an end rail and one in the main frame) are vertically above each other; a pair of crossed levers at each end of the main frame pivotally connected together where they cross each other, the lower ends of each pair of such levers being respectively pivotally connected to the main frame and pivotally mounted in a slot in such main frame, and the upper ends of each pair of levers being respectively pivotally connected to a horizontal end rail and pivotally mounted in the slot in such end rail so that the end rails, and with them the upper frame, may be raised from and lowered onto the main frame by means of the lever system; a shaft extending from one end of the main frame to the other and mounted for rotation relative to such main frame; a bell-crank lever mounted on one end of the shaft; a link pivotally connected at one end to the bell-crank lever and at the other to the pivotal point of one pair of crossed levers;

a crank lever mounted on the other end of the shaft; a link connected at one end to the crank lever and at the other to the pivotal point of the other pair of crossed levers; and a coil-spring

disposed horizontally between the upper ends of each pair of crossed levers.

JACK UNTERHALTER.
